US00D976040S

(12) **United States Design Patent** (10) Patent No.: **US D976,040 S**
(45) Date of Patent: ** Jan. 24, 2023

(54) **BENCH**

(71) Applicant: **URBIDERMIS, S.L.**, La Roca del Vallès (ES)

(72) Inventors: **Gonzalo Milà Valcàrcel**, Barcelona (ES); **Miguel Milà Sagnier**, Barcelona (ES)

(**) Term: **15 Years**

(21) Appl. No.: **35/511,963**

(22) Filed: **May 12, 2021**

(80) **Hague Agreement Data**

Int. Filing Date: **May 12, 2021**

Int. Reg. No.: **DM/214413**

Int. Reg. Date: **May 12, 2021**

Int. Reg. Pub. Date: **Jun. 4, 2021**

(51) **LOC (14) Cl.** **06-01**

(52) **U.S. Cl.**

USPC **D6/717**

(58) **Field of Classification Search**

USPC D6/334, 349, 355, 370, 371, 372, 373, D6/379, 380, 381, 702, 716, 717

Primary Examiner — Steven J Czyz

(74) Attorney, Agent, or Firm — McCormick, Paulding & Huber PLLC

(57) **CLAIM**

The ornamental design for a bench, as shown and described.

DESCRIPTION

1. Bench

1.1 : Perspective

1.2 : Front

1.3 : Right

1.4 : Top

1.5 : Left

1.6 : Bottom

1.7 : Back

1.8 : Cross sectional

The portions of the bench shown in broken lines form no part of the claimed design; the bench is shown with a break in its width that indicates the indeterminate length or width of the design; the appearance of any portion of the article between the break lines forms no part of the design; figure 1.8 shows a section cut along plane 1.8 of Figure 1.3.

1 Claim, 8 Drawing Sheets
